GOLF BALL DRIVING PRACTICE APPARATUS

Filed April 12, 1928

UNITED STATES PATENT OFFICE

THOMAS H. MACGEORGE, OF SEATTLE, WASHINGTON

GOLF-BALL-DRIVING PRACTICE APPARATUS

Application filed April 12, 1928. Serial No. 269,373.

This invention relates to golf ball driving practice apparatus; and its object, generally, is the provision of inexpensively constructed and efficient apparatus of this character with which the skill and power of a player in the use of a golf club may be acquired and improved.

More specific objects and advantages of the invention will appear in the following description.

The invention consists in the novel construction, adaptation and combination of parts as will be hereinafter described and claimed.

15 In the accompanying drawing,—

Figure 1 is a side elevation of apparatus embodying the present invention illustrated in its form now preferred by me; Fig. 2 is a transverse vertical section of Fig. 1; Fig. 3 20 is an end elevation taken from the left hand side of Figs. 1 and 2; and Fig. 4 is a horizontal section on line 4—4 of Fig. 2.

In carrying out the invention I provide an open front tent-like structure of canvas or other suitable material having two side walls 5, a rear wall 6 and a top wall 7 extending forwardly from the rear wall and connected to the upper edges of the rear portions of the side walls. The top wall slopes upwardly 30 from the rear to its front edge 8 which is located at about the midlength of the structure.

The side walls are desirably arranged to diverge from back to front and, forwardly 35 of their connection with the top wall, said side walls are formed to provide tapering wing extensions 5¹.

The tent is suspended at about its midlength by means of straps 9 attached to the 40 upper ends of poles 10, one at each side of the tent. The rear end of the tent is suspended at the respective corners by means of straps 11 attached to the upper ends of poles 12.

45 Said poles 10 and 12 are disposed exteriorly of the tent and in spaced relation therewith so as not to interfere with the flexing of the tent material when struck with a ball.

Said poles are secured or held in operative 50 positions as by means of guys such as 13.

The lower edges of the back and side walls of the tent may be secured by means of pegs or, preferably, as shown, by being connected by means of seizings 14 with heavy bodies such for instance as bags 15 containing sand, to assure a surface adapted to yieldingly give at all points which may be exposed to the impact of a driven ball. 55

The space within the tent and below the top wall constitutes a chamber which is divided by means of a curtain arranged transversely of the tent and depending from said top wall. 60

This curtain is disposed in spaced relation from the back wall 6 and is comprised, preferably, of two sheets 16, 17, of canvas or an equivalent located in substantially the same vertical plane with each other and extending from or near the respective side walls 5 to overlap each other horizontally at about the 65 midwidth of the tent chamber as shown in Figs. 3 and 4, in a manner to present a two-fold thickness at the approximate point at which a ball, driven in a true line corresponding to natural driving conditions, would impact in its flight, against the curtain. 70

The bottom of the side walls of the tent are connected at the front and rear by stays 18 and 19 respectively with suitable securing means such for example as bolts 20 secured in 80 the floor or ground.

A player standing in front of the tent drives a ball into the tent chamber and against the curtain 16—17 either directly or through incidence with respect to one of the 85 side walls 5 in the event that the ball in its flight should strike such a wall. The ball encountering the curtain will cause the latter to be forced backwardly to an extent proportional to the velocity of the ball. 90

The amount of the rear deflection of the curtain is the measure of its force and also the distance at which the ball would travel if unconstrained. The use of two overlapping curtain members permit the curtain to bulge, so to speak, responsive to the force with which a ball strikes the curtain without unduly stressing the tent structure. 95

The player's stand may be between the leads 5¹ of the tent or at any distance there- 100

in front according to the proficiency and strength of the player.

What I claim is:—

A golf-ball practice apparatus comprising in combination, a tent structure unprovided with a floor and having a back wall, a top wall extending forwardly from said back wall, and side walls connected to said back and top walls and said side walls protruding 10 in diverging relation with respect to each other forwardly of the front edge of the top wall, tent supporting poles disposed exteriorly of the tent and in spaced relation thereto, weight means connected to the lower portions 15 of the back and side walls of the structure for holding the same down, said means being adapted to present a yielding surface coextensive with the length thereof, and a transversely arranged curtain depending from said 20 top wall and in spaced relation from said back wall, said curtain being formed centrally of its width of two overlapping members, said overlap providing a double thickness target to the impact of a driven ball.

25 Signed at Seattle, Washington, this 2nd day of April, 1928.

THOMAS H. MacGEORGE.
